UNITED STATES PATENT OFFICE

2,189,521

PICTURE FRAME

Wyatt M. King, South Haven, Mich., assignor to
S. E. Overton Company, South Haven, Mich.

Application July 31, 1939, Serial No. 287,610

6 Claims. (Cl. 40—152)

This invention relates to picture frames and has for its objects:

First, to provide a new and improved picture frame covered with leather or the like.

Second, to provide such a frame which has a desirable finished appearance but which can be produced inexpensively.

Third, to provide such a frame in which strips of leather may be employed to cover a base frame and in which the joints between the leather strips are fully concealed.

Other objects and advantages pertaining to details and economies of construction and operation will appear from the description to follow.

Preferred embodiments of my invention are illustrated in the accompanying drawings, in which:

Fig. 1 is a front view of a frame made in accordance with my invention.

Fig. 2 is a detail sectional view taken on the line 2—2 of Fig. 1.

Fig. 3 is a view of the wire employed in the picture frame shown in Fig. 1 with portions broken away.

Fig. 4 is a detail sectional view taken on line 4—4 of Figs. 1 and 5.

Fig. 5 is a detail back view of the frame showing the construction thereof with certain parts eliminated.

Fig. 6 is a detail sectional view taken on line 6—6 of Fig. 5 showing the method of attaching metal strip members to overlie the joints in the leather covering on the frame.

Fig. 7 is a perspective view of one of the metal members used to conceal the joints between the leather.

Fig. 8 is a front view of a different form of my invention.

Fig. 9 is a detail sectional view taken on line 9—9 of Fig. 8.

Fig. 10 is a back view of the frame shown in Fig. 8 showing the method of attaching the wire.

Fig. 11 is a fragmentary view of a portion of the wire.

Fig. 12 is a detail view of a corner of a different form of my invention.

My improved picture frame 1 consists of a rectangular base frame 2 made of wood or other suitable material rabbeted at the back as at 3. The wire 4 consists of a rectangular metal frame-like member which fits within the aperture 5 of the frame and has ears 6 extending from the corners thereof to fit in the rabbeted portion 3. Fitted in the rabbeted portion 3 is the glass 7, the picture 8 and a suitable backing 9. A further rabbeted portion 10 in the back of the frame is

covered by a member 11 which is fastened to the rear of the frame which forms a slide to receive the back 12 of the frame which has the projecting edge 13 which fits slidably in the groove beneath the member 11 as is common in the picture frame art.

The base frame 2 is covered with a plurality of strips 14 of leather or other flexible material suitable for covering the frame, which cover the face of the base frame and are mitered to form miter joints at the corners. The strips 14 are adhesively secured to the base frame.

The base frame is provided with apertures 15 extending therethrough at the joints of the strips of leather or the like and at the back of the frame the apertures are countersunk as at 16 on the face of the frame, and overlying the joints between the leather strip are metal strip members 17. These members are formed of relatively soft metal and are shaped to fit the surface contour of the frame and to overlie the joints between the leather. Their ends 18 extend downwardly so as to give complete concealment of the joint and pins 19 extend from the backs thereof at points spaced between the ends. The pins 19 are screw threaded as indicated at 20 to receive nuts 21 which have cooperating screw threads and are provided with apertures 22 to fit a spanner wrench.

The metal strip members 17 are formed of relatively soft metal and are initially formed to substantially conform to the surface contour of the frame. The ends are bent slightly down, however, so that when the metal members are placed on the frame preparatory to attachment, they bow up slightly as indicated in Fig. 6. The pins 19 fit through the apertures 15 in the base frame and the nuts 21 are screwed down into engagement with the back of the base frame and into the countersunk portions 16 to pull the metal strip member 17 down into tight fitting engagement with the face of the frame.

The pins 19 are ordinarily made of a length greater than necessary to extend through the apertures 15 to facilitate application of the nuts 21 thereto when the metal strip members are being installed. After the metal strip members have been pulled down into tight engagement with the face of the frame, the projecting ends may be cut off. In Fig. 6 I show the pin before the end has been cut off, whereas in Fig. 4 the end has been cut off.

The metal members 17 are made to harmonize with the wire 4 and to extend therefrom over the

joints between the strips of leather or the like and to form substantially continuations of the wire, giving a very pleasing appearance.

I have found that by employing the above described construction, it is possible to make use of strip leather which avoids the waste attendant upon cutting a complete frame cover from a single piece of leather. I have also found that it is easier to fit the leather over the base frame if the strips are employed.

By employing the projecting pin 19 and the nuts, I am able to pull the metal strip member 17 down into tight engagement with the face of the frame and I can install these members quite easily and can adjust them before finally tightening the nuts to make sure that the joints between the strips of leather or the like are covered. The metal strip members 17 are retained permanently in place when the nuts are tightened and there is not any appreciable difficulty in displacement thereof as would be the case if other fastening means were employed.

In Figs. 8-11, I show a slightly different form of my invention. The frame 101 is substantially identical with the above described frame. The wire 104 differs slightly in cross section and is provided with ears 106 which are bent around into the rabbeted portion 103 of the frame, as shown in Fig. 9, to hold the wire in place. The ends of the members 117 are notched as indicated at 23 to fit the corners of the wire. The result is substantially the same as that above described.

In Fig. 12, I show a slightly different form of my invention. There, instead of providing a miter joint between the leather strips 214, I provide an additional square of leather or the like 24 covering the corner. The members 217 cover the joints between the strip 214 and the square 24 in substantially the same way that the members 17 and 117 cover the joints between the strips 14 and 114 in the other forms of the invention described.

It will be apparent that the structure which I have provided can be made very inexpensively from strip leather and that it will be a permanent structure which will last indefinitely and which will have a desirable appearance. I have described several forms of my invention but have not exhausted all possible forms. It will be apparent from the above description that other forms of the invention may be employed and I have defined my invention in the claims.

Having thus described my invention, what I claim as new and desire to secure by Letters Patent is:

1. In a picture frame, the combination of a substantially rectangular base frame, a plurality of strips of leather or the like covering the face of said base frame and having their ends mitered to form miter joints at the corners of said frame, apertures through said base frame at the joints of said strips, a wire fitting in said frame, and metal strip members overlying the joints of said strips and concealing the same, and extending from and forming continuations of said wire, each having a screw threaded pin projecting from the back and spaced from the ends thereof and extending through one of said apertures, said members being shaped to conform to the surface contour of the frame, each having a nut threadedly engaging its pin and the back of the frame and retaining said member in position in tight engagement with the face of the frame at the juncture of said leather strips, the back of said frame being

countersunk at said apertures to receive said nuts.

2. In a picture frame, the combination of a substantially rectangular base frame, a plurality of strips of leather or the like covering the face of said base frame and having their ends mitered to form miter joints at the corners of said frame, apertures through said base frame at the joints of said strips, a wire fitting in said frame, and metal strip members overlying the joints of said strips and concealing the same, and extending from and forming continuations of said wire, each having a screw threaded pin projecting from the back and spaced from the ends thereof and extending through one of said apertures, said members being shaped to conform to the surface contour of the frame, each having a nut threadedly engaging its pin and the back of the frame and retaining said member in position in tight engagement with the face of the frame at the juncture of said leather strips. 20

3. In a picture frame, the combination of a substantially rectangular base frame, a plurality of strips of leather or the like covering the face of said base frame and having their ends mitered to form miter joints at the corners of said frame, 25 apertures through said base frame at the joints of said strips, and metal strip members overlying the joints of said strips and concealing the same, each having a screw threaded pin projecting from the back and spaced from the ends thereof and extending through one of said apertures, said members being shaped to conform to the surface contour of the frame, each having a nut threadedly engaging its pin and the back of the frame and retaining said member in position in tight engagement with the face of the frame at the juncture of said leather strips. 30

4. In a picture frame, the combination of a base frame, a plurality of strips of leather or the like extending longitudinally on and covering the face of said base frame with their ends in abutting relationship, apertures through said base frame at the joints between said strips, a wire fitting in said frame, and metal strip members overlying the joints of said strips and concealing the same and extending from and forming continuations of said wire, each having a screw threaded pin projecting from the back and spaced from the ends thereof and extending through one of said apertures, said members being shaped to conform to the surface contour of the frame, each having a nut threadedly engaging its pin and the back of the frame and retaining said member in position in tight engagement with the face of the frame at the juncture of said leather strips. 45

5. In a picture frame, the combination of a base frame, a plurality of strips of leather or the like extending longitudinally on and covering the face of said base frame with their ends in abutting relationship, apertures through said base frame at the joints between said strips, and metal strip members overlying the joints of said strips and concealing the same, each having a screw threaded pin projecting from the back and spaced from the ends thereof and extending through one of said apertures, said members being shaped to conform to the surface contour of the frame, each having a nut threadedly engaging its pin and the back of the frame and retaining said member in position in tight engagement with the face of the frame at the juncture of said leather strips. 60

6. The combination of a picture frame made up of a plurality of jointed pieces, apertures through said frame at the joints, a wire fitting in 70

75

said frame and metal strip members overlying the joints and concealing the same and extending from and forming continuations of said wire, each having a screw threaded pin projecting from the back and spaced from the ends thereof and extending through one of said apertures, said

members being shaped to conform to the surface contour of said frame, each having a nut threadedly engaging its pin and the back of the frame and retaining said member in position in tight engagement with the face of the frame. 5

WYATT M. KING.
